UNITED STATES PATENT OFFICE.

MILO E. RICE, OF LOS ANGELES, CALIFORNIA.

ARCH AND HEEL SUPPORT.

941,464.

Specification of Letters Patent. Patented Nov. 30, 1909.

Application filed August 19, 1907. Serial No. 389,138.

To all whom it may concern:

Be it known that I, MILO E. RICE, a citizen of the United States, residing at Los Angeles, county of Los Angeles, State of California, have invented new and useful Improvements in Arch and Heel Supports, of which the following is a specification.

My invention relates to means which are worn inside of boots or shoes for supporting the arch of the instep either to prevent the same from breaking down, or if impaired to support the parts to enable them to regain their normal shape and condition, and also to provide a certain amount of resiliency under the heel to take off a portion of the jar caused in walking; and the objects are to provide a simple and effective instep support which is capable of adjustment, and a heel extension to take off a portion of the ordinary jar in walking. I accomplish these objects by the device described herein and illustrated by the accompanying drawings in which;

Figure 1 is a bottom perspective view of the support removed from the shoe. Fig. 2 is a side view of the same. Fig. 3 is a side view showing the same in place in a shoe, a portion of the shoe being cut away for clearness of illustration. Fig. 4 is a side view showing another manner of securing the lacing thongs to the body.

In the drawings the body 5 is a piece of leather or any other suitable material, preferably sole leather, which is cut and molded to conform to the arch part of the foot under the instep and to the heel of the wearer, so as to fit into any given size or number of boot or shoe. The front edge 6 is brought to a thin edge and preferably extends toward the front of the shoe 7 so as to come beneath the ball 8 of the foot 9 of the wearer. Near the front end and to the bottom of the body is secured a thong strip 10 which is of canvas or other suitable material. This thong strip is provided with eyelet holes 11 into which is received the lacing thong 12, which also passes through eyelet holes 13 in the heel plate 14 which is secured to the body portion by rivets 15. Heel plate 14 is of resilient metal and is cut away in the central portion as best shown in Fig. 1, and the rear portion 16 is bent downwardly as best shown in Fig. 2 so that when in place in the shoe the rear end 16 of the heel plate would bear on the bottom of the shoe. A reinforcing plate 17 of the same

configuration as the rear portion of the heel plate is likewise secured upon the rear end of the body to stiffen the same. The heel plate is provided to take off a portion of the jar caused in walking and if it is not required the arch support could have secured at the rear portion thereof a thong strip with holes or eyelets therein similar to strip 10. By this construction an arch and heel support is provided which can be removed from the shoe when desired, and the lacing thong can be tightened or loosened to provide a higher or lower arch support. The thong also being somewhat resilient will give slightly when the weight is thrown on the body thereby producing greater resiliency than if the thong were omitted.

Where cheapness of construction is an object lacing holes 18 may be provided in the body as shown in Fig. 2 and the lacing thong could be used therein to give a higher or lower arch.

Having described my invention what I claim is;

1. A removable flexible body piece conforming to the instep arch; and non-metallic, flexible, adjusting means secured to the body piece near the ends thereof, said adjusting means passing longitudinally the body piece from near one end to near the other end thereof, whereby the arch may be raised or lowered as desired.

2. A body piece conforming to the instep arch; a thong strip secured to said body piece on the under side thereof near the front end, said thong strip having eyelet holes therein; a heel plate secured to said body near the rear end thereof, said heel plate having eyelet holes therein; and a lacing thong in said eyelet holes.

3. A body piece conforming to the instep arch; a thong strip secured to said body piece said thong strip having eyelet holes therein; a heel plate having the central portion thereof cut out secured to said body piece near the rear end thereof; said heel plate having eyelet holes at the forward end thereof and having the rear end thereof bent downwardly; and a lacing thong in said eyelet holes.

4. As an improved article of manufacture a removable arch support for boots and shoes formed of suitable material shaped to conform to the foot at the heel and arch; said support having a transverse row of eyelet holes near the front and another trans-

verse row of eyelet holes near the back thereof; and a lacing thong in said eyelet holes alternately passing through the holes at the front and back.

5. As an improved article of manufacture a removable arch support for boots and shoes formed of suitable material shaped to conform to the foot at the heel and arch; a lacing thong adjustably secured to the front and rear of said support and means for imparting resiliency to the rear portion of said support.

6. A removable flexible body piece conforming to the instep arch, and a lacing thong secured near the ends thereof to hold the ends from spreading, said thong running longitudinally said body piece.

7. An arch support for shoes comprising a single continuous plate of resilient material, members disposed under the plate with their inner ends normally separated and provided with eyelets adjacent said inner ends, fastenings for securing the outer ends of the members to the plate, and a lacing passing through the eyelets for drawing the members together to vary the curvature of the plate in the direction of its length.

In witness that I claim the foregoing I have hereunto subscribed my name this 13th day of August, 1907.

MILO E. RICE.
